HENRY L. MILLS, OF ST. PAUL, MINNESOTA.

Letters Patent No. 69,829, dated October 15, 1867.

ARTIFICIAL LEG.

The Schedule referred to in these Letters Patent and making part of the same.

TO ALL WHOM IT MAY CONCERN:

Be it known that I, HENRY L. MILLS, of St. Paul, in the county of Ramsey, and State of Minnesota, have invented a new and useful improvement in Artificial Legs; and I do hereby declare that the following is a full, clear, and exact description thereof, which will enable others skilled in the art to make and use the same, reference being had to the accompanying drawings, forming part of this specification, in which—

Figure 1 is a rear view of my improved artificial leg.

Figure 2, a central vertical section longitudinally through the foot, taken in the line xx , fig. 1.

Figure 3 is a cross-section, in the line yy , fig. 1.

Figure 4, a detail view of joint in the leather socket.

Figure 5 is a cross-section, in line ww , fig. 1.

Figure 6, a cross-section, in the line vv , fig. 1.

Figure 7, a cross-section, in the line zz , fig. 2.

Figure 8, a detached perspective view of the irons on the foot.

Similar letters of reference indicate like parts.

This invention relates to an improved method of constructing an artificial leg, and consists in several devices and arrangements for securing comfort and convenience to the wearer, and making a strong, cheap, and durable artificial limb. The principal feature of this improvement is the perfect adaptation of a leather socket for the stump, which may be easily separated from the frame of the leg and allowed to remain on the stump, for its protection, while sleeping, and as rapidly readjusted for use, or which may be simply loosened on the frame to relieve any pressure, and be ready at a moment's notice for readjustment, to be ready for walking. There are several minor devices, important in themselves and their combination, to be hereinafter described. But only the improvements of my invention are specially exhibited and described, and a complete limb has other well-known attachments.

A represents a wooden foot, in the middle of which is a large mortise, α , extending longitudinally from the forward part of the heel to the back part of the instep, with vertical sides, the forward end of the mortise sloping forward considerably from the top to the bottom, and the rear end nearly vertical or sloping backward a little from the top to the bottom, as shown in fig. 2. In this mortise α is fitted a straight wooden peg, B, extending down from and forming a part of an ankle-piece, B', and nearly level at the lower end with the sole of the foot. The wooden block formed of the peg B and ankle-piece B' is pivoted transversely at α to lugs $i i$, on an iron cap-plate, d, to make the ankle-joint; and the cap-plate d, seen in detail, fig. 8, is secured to the upper side of the foot by rivets ee , which pass through the heel from a bottom plate, d' , by which arrangement the wood is bound firmly, so that it cannot split. An iron supporting-frame, composed of four strong strips, gg , are riveted together at opposite points upon the ankle-piece B', the rivets crossing each other at right angles, as seen in fig. 6, to give the wood greater strength at a point where it is especially required. Above the ankle-piece B' the frame gg expands, to conform in shape to the calf of the leg, and enclose the socket C for amputations below the knee, while the frame may be extended as required for enclosing sockets to fit the stumps of that class of amputations above the knee. The frame strips gg are united by two or more bands, the lower one, h , being made of metal, and the upper one, h' , of metal and leather combined, as shown in fig. 2. The bands are riveted to the bars gg of the frame, thus forming a stiff and firm bed-support for the leather socket C, which is enclosed in the frame. The socket C is adapted to the stump when it is made, by cutting the leather to fit the stump while dry as nearly as possible. The socket is then sewed together, and afterwards wet and thoroughly soaked with water, to make the leather soft and pliant, in order then to fit it carefully and exactly to all the bearing points of the stump, which perfect adaptation to the surface of the stump the leather socket will retain when dry, and consequently always be easy and comfortable to the wearer. The socket C is attached to the person of the wearer by straps kk fastened to the upper edge of the sides of the socket, and is attached to the iron frame gg by wing straps $k'k'$, connected by buttons, snap-hooks, or buckles mm , by which arrangement it will be seen that the socket may be readily loosened or detached from the frame gg , to remain on the stump for its protection, while the frame may be fastened on again quickly. In order to secure the socket firmly to the iron frame a bar, n , is pivoted to the band h in the rear of the leg, the upper end of which bar

catches on an iron plate, *p*, riveted to the lower part of the socket *C*, and held in the catch by an India-rubber or any suitable spring, *s*, placed on the lower end and bearing against the ankle-piece *B'*. For releasing the catch of the connecting-bar *n*, to detach the frame *g g* from the socket and take it off entirely, it is only necessary to bear the toe of the shoe or boot on the other leg against the lower end of the bar, to press in the spring *s*; the frame is then taken off in the same manner a boot is taken off of one leg by the aid of the other boot. Below the spring *s*, and bearing up against it, is attached a vertical heel-spring, *u*, formed of a pin covered with India-rubber tubing. The lower end of the pin sets in a hole in the upper side of the heel, in which it moves up and down, while the elasticity of the rubber regulates the position of the foot *A* in walking, by bearing down the heel at every step forward, as the foot swings on the pivot of the ankle-joint at *c*, and the peg *B* plays back and forth in the mortise *a*. The spring *u* may be attached at one end by a leather flap or a hinge.

Having thus described my invention, I claim as new, and desire to secure by Letters Patent—

1. The adjustable and movable leather socket *C*, constructed, applied, and operating substantially as and for the purposes herein described.
2. The combination of the iron frame *g g*, secured by rivets to the ankle-piece *B'*, the bands *h h'*, the straps *k' k'*, and the socket *C*, all constructed, arranged, and operating substantially as and for the purposes set forth.
3. The spring-bar *n*, pivoted to the band *h*, in combination with the socket *C*, arranged and operating substantially as and for the purpose specified.
4. The plates *d d'* on the upper and lower sides of the heel of the foot *A*, secured by the rivets *e e*, substantially as and for the purposes described.
5. The peg *B* and ankle-piece *B'*, pivoted to the plate *b* and fitted in the mortise *a*, in combination with the frame *g g* and the foot *A*, constructed, arranged, and operating substantially as and for the purposes herein set forth.
